UNITED STATES PATENT OFFICE.

CHARLES MIRMILLO, OF OAKLAND, CALIFORNIA, BY SARAH E. HAYES, GUARDIAN,
OF OAKLAND, CALIFORNIA.

BREECH-BLOCK MECHANISM.

1,382,796.

Specification of Letters Patent. Patented June 28, 1921.

Application filed August 16, 1920. Serial No. 404,018.

To all whom it may concern:

Be it known that SARAH E. HAYES is a citizen of the United States, residing at Oakland, in the county of Alameda, State of California, and the duly-appointed guardian of CHARLES MIRMILLO, who has invented certain new and useful Improvements in Breech-Block Mechanisms, of which the following is a specification.

10 This invention relates to improvements in breech block mechanisms, especially for heavy artillery, the principal object of the invention being to provide a block which has a greater depth than those now used, 15 thus allowing a heavier charge to be placed in the gun.

Another object is to provide the block with a simple means for guiding and maintaining it in position.

20 The above and other objects are accomplished by means of such structure as will appear by a perusal of the following specification taken in connection with the accompanying drawings, in which—

25 Figure 1 is a side elevation of the cannon. Fig. 2 is a top plan view thereof.

Fig. 3 is a sectional view taken on a line 3—3 of Fig. 1.

30 Fig. 4 is a section taken on a line 4—4 of Fig. 2.

Referring to the characters of reference in the drawings, the numeral 1 denotes the barrel carriage on which is mounted the barrel 2. Toward the breech of the barrel is 35 pivoted an arm 3 as at 4, at the rear end of which is pivoted a bracket 5 carrying the breech block 6 thereon.

Fixed on each side of the bracket 5 are grooved guides 7 engaging tracks or guide

bars 8 formed with the carriage 1 and curved 40 radial with the pivotal connection 4 of the arm 3, thus allowing the block to be swung about its pivotal connection with the arm 3 and insuring that when again raised it will be in proper alinement. 45

The usual fastening or securing mechanism is employed in the block. Vertical movement of the barrel 2 is provided for by means of suitable gearing 9 and horizontal swivel movement by means of suitable gearing 10. A suitable recoil mechanism is provided, which consists of parallel cylinders 11 in which are springs 12, the barrel having arms 13 projecting into the plane of the cylinders and bearing against the springs. In 55 the block sleeve 6^a is a block 14 slideable therein and adapted to be projected or slid into the breech of the barrel a desired distance by means of gearing 15. When the block 14 is withdrawn, the sleeve 6 may be 60 swung about the pivotal connection of the bracket 5 with the arm 3, or the arm 3 may itself be moved vertically to the limits of the guides 8.

Having described the invention, what is 65 claimed is:

A breech mechanism for cannon comprising an arm pivoted to the barrel carriage, a bracket pivoted to the arm and carrying a breech block structure, and co-operating 70 guides on the bracket and carriage for maintaining the alinement of the breech mechanism and holding the same in position when the arm is moved relative to the carriage.

In witness whereof, I hereby affix my sig- 75 nature.

SARAH E. HAYES,
Guardian of Charles Mirmillo.
